CLAIM

The ornamental design of a furniture leg with frame as shown and described.

DESCRIPTION

FIG. 1 is a front perspective view of the furniture leg with frame, illustrating the new design;
FIG. 2 is a magnified front perspective view thereof;
FIG. 3 is a magnified back perspective view thereof;
FIG. 4 is a left side elevation view thereof;
FIG. 5 is a front elevation view thereof;
FIG. 6 is a back elevation view thereof;
FIG. 7 is a right side elevation view thereof;
FIG. 8 is a top plan view thereof; and,
FIG. 9 is a bottom plan view thereof.

The dashed broken lines depict portions of the article or environment that form no part of the claimed design. The dash dot dash broken lines depict boundaries of the article that form no part of the claimed design.

1 Claim, 5 Drawing Sheets
